[57] CLAIM

The ornamental design for a digging tool, substantially
as shown.

DESCRIPTION

FIG. 1 is a front elevational view of a digging tool,
showing my new design,

FIG. 2 is a side elevational view thereof.

FIG. 3 is an enlarged fragmentary perspective view of
the lower front portion thereof, and

FIG. 4 is an enlarged fragmentary rear elevational view
thereof.

FIG. 1.

FIG. 2.

FIG. 4.
